[57] CLAIM

The ornamental design for a counter top, as shown and described.

DESCRIPTION

FIG. 1 is a top perspective view of a counter top showing my new design;

FIG. 2 is a front elevational view;

FIG. 3 is an elevational view showing one end, with the other end being substantially identical;

FIG. 4 is a top plan view;

FIG. 5 is a rear elevational figure;

FIG. 6 is a bottom plan view; and

FIG. 7 is an enlarged cross-sectional side view thereof, a portion of the center being broken away for convenience of illustration.
